UNITED STATES PATENT OFFICE.

JOHN HOLLAND LETZ, OF CROWN POINT, INDIANA, ASSIGNOR TO THE LETZ MANUFACTURING COMPANY, OF CROWN POINT, INDIANA, A CORPORATION OF INDIANA.

GRINDING-BUR.

1,244,515.

Specification of Letters Patent. Patented Oct. 30, 1917.

Application filed January 17, 1917. Serial No. 142,802.

To all whom it may concern:

Be it known that I, JOHN HOLLAND LETZ, a citizen of the United States, and a resident of Crown Point, in the county of Lake 5 and State of Indiana, have invented certain new and useful Improvements in Grinding-Burs, of which the following is a full, clear, and exact specification.

My invention is concerned with grinding 10 burs of the type shown in the Letz Patent No. 437,699, and is designed to produce a dress of the bur that will grind more rapidly and economically than can be done with the dress shown in the aforesaid patent.

15 To illustrate my invention, I have annexed hereto a single sheet of drawings, in which the same reference characters are used to designate identical parts in all the figures, of which,—

20 Figure 1 is a view of the face of a complete bur containing my invention;

Fig. 2 is a section on the line 2—2 of Fig. 1; and

25 Fig. 3 is an enlarged view of a portion of Fig. 1.

The body of the bur is made up preferably of a thin annular casting, which may be reinforced on its back by employing one or more annular ribs r . Its upper or grinding face is generally flat, except as it is broken by the grinding ribs to be described, and which it will be understood are ordinarily cast integral with the body and ground off so as to form on all of them 30 cutting edges and grinding surfaces in the same plane and adapted to coöperate with similar edges and surfaces similarly formed on the similar ribs of the opposed face of the companion bur.

40 The ribs are preferably arranged in groups substantially triangular in their general outline, preferably six in number. The ribs going to make up each of the six groups are preferably the same, so that the description of one group will suffice for all.

45 Considering an imaginary radial line running through the center of each group (such as a central vertical line in Fig. 1) as the base line for the purposes of description, the main ribs a , b , c , d , and e in a group are set substantially parallel to each other and at an angle of say sixty degrees to the radial base line, and are preferably interrupted or broken so that each rib is 50 made up of a plurality of sections, such as

a , a' , a^2 , b , b' , b^2 , b^3 , c , c' , c^2 , c^3 , d , d' , d^2 , e , e' and e^2 . Intersecting these main ribs are the baffle ribs f , g , h , j , k , and l , also broken into sections f , f' , f^2 , g , g' , g^2 , h , h' , h^2 , j , j' , k , k' , and l , these baffle ribs being parallel 60 to each other and substantially parallel to the base line. These sections of the baffle ribs are, as it will be noted, in groups between the main ribs, and together with the main ribs, or their sections, form a series of partially open sockets having converging sides, such for instance as f and b , g and c , f' and c' , k' and c^2 , and so on. The main ribs a , b , c , and d of any series begin at such a point relative to the main ribs a and a' of 65 the adjacent series as to form a triangular open space o having no ribs between each series of groups. I may employ additional angular ribs p , p' , p^2 , p^3 , p^4 , p^5 and p^6 , at the periphery of the disk, to slow up the 70 grain in its passage from the center to the circumference and to insure its being ground.

The operation of the burs will be readily understood by those skilled in the art. The 80 main and baffle ribs of one bur coöperate with the baffle and main ribs, respectively, of the companion bur in a direct shearing action, while the centrifugal force of the rotating bur forces the grain always outward, and the converging ribs forming 85 pockets crowd the grain up from the flat surfaces of the burs so that it will necessarily be brought into the shearing plane formed by the flat surfaces of the ribs. 90

What I claim as new, and desire to secure by Letters Patent of the United States, is:

1. A grinding bur consisting of a generally flat disk having a series of grinding ribs projecting therefrom and having their 95 flat top surfaces in the same plane and forming shearing edges, said ribs consisting of plural series of parallel ribs separated by other similar series of parallel ribs interrupted at intervals and extending at acute 100 angles to the first-mentioned series, sections of one series of ribs being interposed between pairs of the other series of ribs so as to form plural series of acute angles with small openings at their outwardly directed 105 apexes said series of angles extending in the general direction of the adjacent periphery, and each of said series of angles being separated from the adjacent series by a considerable plane space. 110

2. A grinding bur consisting of a generally flat disk having a series of grinding ribs projecting therefrom and having their flat top surfaces in the same plane and forming shearing edges, said ribs consisting of plural series of parallel ribs interrupted at intervals and separated by other similar series of parallel ribs likewise interrupted at intervals and extending at acute angles to the first-mentioned series, sections of one series of ribs being interposed between pairs of the other series of ribs so as to form plural series of acute angles with small

openings at their outwardly directed apices, said series of angles extending in the general direction of the adjacent periphery, and each of said series of angles being separated from the adjacent series by a considerable plane space.

In witness whereof, I have hereunto set my hand and affixed my seal, this 16th day of December, A. D. 1916.

JOHN HOLLAND LETZ. [L. S.]

Witness:

JOHN HOWARD McELROY.
